PAPER TOWELING

Philip Masnick, New York, N.Y., assignor to The Procter & Gamble Company, Cincinnati, Ohio, a corporation of Ohio

Filed Oct. 17, 1966, Ser. No. 4,295

Term of patent 14 years

(Cl. D59—2)

The figure is a plan view of paper toweling showing my new design; the toweling is shown broken away by dot-dash lines for convenience of illustration, the portion between the decorative borders being plain and unornamented.

I claim:

The ornamental design for a paper toweling, as shown and described.
